UNITED STATES PATENT OFFICE.

JAMES H. SHUNK, JR., OF ROSCOE, ILLINOIS

PYROTECHNIC WHEEL.

Application filed May 14, 1926. Serial No. 109,000.

This invention relates to a pyrotechnical wheel of the type adapted to rotate under the impulse supplied by pyrotechnical materials carried thereby.

Pyrotechnical spinning wheels are made in various sizes, some of them being a number of feet in diameter. These wheels carry pyrotechnical units commonly called drivers, adapted to cause the rotation of the wheel and also often carry, in addition, effects, the sole purpose of which is to produce a pleasing appearance when the wheel is rotated. These wheels are normally constructed at the factory where the pyrotechnical drivers and effects are attached and the fuses connected. The railroads and transportation companies require that inflammable and explosive substances, such as pyrotechnical compounds, be enclosed in heavy wooden boxes and a relatively high freight rate is charged. The manufacture of a box of the required character and of a size sufficient to hold a wheel which may be six or eight feet in diameter is very large; also the weight of such a box adds very materially to the transportation cost, the box often materially exceeding in weight the contained pyrotechnics.

It is an object of the present invention to provide a pyrotechnical spinning wheel which can be collapsed so as to occupy but small space during transport.

It is an additional object to provide a wheel of this character which is composed of but few parts and adapted for assembly by unskilled labor.

It is also an object to provide a wheel provided with a felly or rim which is flexible or collapsible, and adapted to positively retain the spokes in place against the effect of centrifugal force.

Other and further objects will appear as the description proceeds.

I have illustrated certain preferred embodiments of my invention in the accompanying drawings, in which—

Figure 1 is an elevation of one form of wheel;

Figure 2 is a side view of Figure 1 with parts broken away;

Figure 3 is a cross section showing the hub construction;

Figure 4 is a view similar to Figure 1, showing a modified form of construction;

Figure 5 is a view of the wheel of Figure 4 as seen from above;

Figure 6 is a view of the wheel of Figure 4 as seen from the side with the rim removed;

Figure 7 is a fragmentary section showing the hub construction; and

Figure 8 is a fragmentary section taken on line 8—8 of Figure 7.

Referring first to the form of construction shown in Figures 1 to 3, the wheel comprises the metallic hub 11 into which are fitted the spokes 12, the ends of which are surrounded by the flexible rim 13. As shown in Figure 3, the hub may be formed of two pieces 14, of case metal, secured together to form the spoke sockets. It is obvious, however, that the hub may be formed of stamped metal or wood or other material if desired. The spokes 12 may be formed of wood or metal tubing or other material. The rim 13 may consist of a flexible strip of metal or of suitable non-combustible material. In the form shown the ends of the rims are provided with the studs 15 upon which are pivotally mounted the screw-eyes 16 connected by the turn-buckle 17. The spokes 12 are provided on their outer ends with the screw-eyes 18 which may pass through the elongated slots 19 in the rim 13, and then be turned at right angles to the slot to maintain the rim in place.

The drivers 20 may be secured to the rim by tying, as indicated at 21. The drivers are connected by the fuse or quick match 22. These drivers may be of any usual construction known in the pyrotechnical art, and their detailed construction forms no part of the present invention. The discharge from the drivers may constitute the entire effect from the wheel or additional effects 23 may be secured to the spokes, these effects being connected by the fuse or quick match 24. The ends of the fuses 22 and 24 may be connected, as indicated at 25, so that both effects and drivers may be simultaneously ignited.

Referring now to the form of construction shown in Figures 4 to 8, the wheel consists of a plurality of separate elements fitted upon the axle 30 and retained in place by the washers 31 and nuts 32. These sections each comprise a hub member 33 and the spoke 34 extending therefrom. In the form shown there are six sections, and as clearly shown in Figures 5 and 6, the spokes of different sections extend at varying angles to

the sections so that the outer ends of all of the spokes are located in a common plane. The meeting faces of the sections are stepped, as indicated at 35 of Figures 5 and 6, 5 and as clearly shown in the section in Figure 8. These steps are so related to the spokes borne by the several sections that when the sections are rotated to bring the steps 35 into engagement the spokes are 10 properly spaced. It will be understood that by releasing one or both of the nuts 32 the sections may be sufficiently separated so that the steps 35 will clear each other and the sections may be rotated to bring all of the 15 spokes together in approximately the same radial direction.

The outer ends of the spokes carry the rim which comprises a plurality of sections 36 which may be formed of any suitable 20 material, such as sheet metal, and which are concaved outwardly, as shown in Figure 5. These sections 36 are hingedly connected at 25 37 to the links 38 adapted to be fitted upon the outer ends of the spokes. These links 38 are provided with elongated slots 39 through which are passed the screw-eyes 40 which are rotated to retain the rim in place. The rim is provided with two short sections 41 which are connected by screw 30 bolts 42 and the turnbuckle 43. The drivers 44 are secured to sections 36 and rest in the concave outer face of the sections. The drivers are connected by the fuse 45 and the 35 spokes may also be provided with the effects 46 connected by the fuse 47. Fuses 45 and 47 may be connected together at 48 for simultaneous ignition.

In the operation of the form of construction shown in Figures 1 to 3, it will be clear 40 that the rim may be removed by loosening the turnbuckle 17 and turning the screw-eyes 18 to pass through the slots 19. The rim then may be closely coiled or bent back and forth upon itself to occupy a very small 45 space. Similarly, the spokes may be withdrawn from the sockets in the hub 14 and placed parallel to each other. The hub then may be packed with the spokes and the rim, all forming a package of very small dimension, which can be readily assembled by unskilled labor to form a wheel. If desired, 50 the drivers and effects need not be attached until the wheel is assembled. In this case the pyrotechnical elements may be packed and shipped in a separate box and the hub, 55 spokes and rim may be shipped without requiring the special containers necessary for pyrotechnics. It will be understood that in the use of the wheel it will be ordinarily 60 supported in a vertical position by means of any suitable metal axle, such as a large spike or bolt extending horizontally from a post or tree.

The form of construction shown in Figures 4 to 8 may be knocked down by remov-

ing the rim as explained in connection with the other form of device, and by then loosening the nut 32 and separating the sections axially and rotating them to bring the spokes together. When so knocked down the wheel occupies a comparatively small space and requires a relatively small shipping container. As with the other form, the drivers and effects may be shipped separately and attached after the wheel is assembled. In this form the axle 30 serves as a pivot about which the wheel rotates under the impulse of the drivers and this axle may be supported in any suitable manner.

I have illustrated certain embodiments of my invention by way of example but it is to be understood that I contemplate such further changes and modifications as may come within the spirit and scope of the appended claims.

I claim:

1. A collapsible pyrotechnic wheel comprising a hub structure, a removable rim, and spokes movable relative to the axis of the hub structure whereby the wheel may be collapsed for transportation.

2. A collapsible pyrotechnic wheel comprising a hub structure, a removable rim, said rim being collapsible, and spokes movable relative to the axis of the hub structure whereby the wheel may be collapsed for transportation.

3. A collapsible pyrotechnic wheel comprising a hub structure, a removable rim, said rim being collapsible and having pyrotechnic driving elements secured thereto, and spokes movable relative to the axis of the hub structure whereby the wheel may be collapsed for transportation.

4. A collapsible pyrotechnic wheel comprising a hub structure, spokes, a removable flexible rim, and means carried by the ends of the spokes to detachably retain the rim in place thereon.

5. A collapsible pyrotechnic wheel comprising a hub structure, spokes removably secured to the hub, a removable flexible rim, and means carried by the ends of the spokes to detachably retain the rim in place thereon.

6. A collapsible pyrotechnic wheel comprising a hub structure, spokes fitted therein, and a removable rim, said rim comprising a strip of flexible material and connecting means for the end of the strip whereby the rim may be tightened about the spokes.

7. A collapsible pyrotechnic wheel comprising a hub structure, spokes fitted therein, a removable rim, said rim comprising a strip of flexible material and connecting means for the end of the strip whereby the rim may be tightened about the spokes, and pyrotechnic driving elements secured to the flexible rim.

8. A collapsible pyrotechnic wheel comprising a hub, radial spoke sockets formed

in the hub, spokes removably fitted in said sockets, a flexible rim adapted to be fitted about the ends of the spokes, securing means about the ends of the spokes, and adjustable means for tightening the rim about the ends 5 of the spokes.

9. A collapsible pyrotechnic wheel comprising a hub, radial spoke sockets formed in the hub, spokes removably fitted in said

sockets, a flexible rim adapted to be fitted about the ends of the spokes, securing means 10 carried by the spokes extending through the rim, and adjustable means for tightening the rim about the ends of the spokes.

Signed at Roscoe, Illinois, this 7th day of May, 1926.

JAMES H. SHUNK, JR.
